Application March 2, 1936, Serial No. 66,547

13 Claims. (Cl. 200—145)

The present invention relates to electric switches and more particularly to the mechanical construction and operation thereof.

Electric switches are widely used for opening and closing power circuits in all types of electric apparatus. Generally speaking, the size and specific design of a switch is determined by the load which it is required to control. Thus, a switch is limited as to the size of the load which it can control by the amount of current which it can carry in the closed condition and by the amount of power which it can dissipate in an arc when it interrupts a circuit. The amount of current which a switch can carry is determined by the heat generated in the switch due to the resistance of the switch. The load which a switch interrupts is measured roughly by the product of the closed circuit current and the open circuit voltage. The interrupting capacity of the switch is determined by the arc which it can extinguish.

The tendency for an arc to form and to maintain itself after being formed increases both with the voltage and current of the circuit. Generally, the limit of the interrupting capacity of the switch is determined largely by the heating effect of the arc incident to the interruption of the circuit. If this arc is permitted to persist for a considerable time it obviously will heat the contacts of the switch more than if it is extinguished promptly so that generally of two similar switches the one which extinguished the arc most quickly after the formation thereof will have the greater interrupting capacity.

Arches which form between the contacts of a switch as they open may be divided roughly into two general classes: Those that have the appearance of a spark and those that have the appearance of a flame. While every arc will not fall readily into one class or the other, the recognition of the two classes aids the study of arcs. The spark is the less severe of the two types. It usually has a blue color and is accompanied by a crackling sound. A telephone receiver or speaker connected to produce as sound, the variations of current or voltage of the arc, will emit a crackling sound accompanied by a sharp thump. The flame persists for an appreciable interval of time. It gives off a bright colored light such as red or yellow and is accompanied by a hiss or a roar both from the arc and the speaker. The thump from the speaker which indicates the final interruption of the current is comparatively weak in the case of the flame. An arc which in appearance resembles both the

spark and the flame will produce a frying noise in the speaker.

A load which produces only a spark at the contacts as the gap opens, generally is well within the capacity of the switch, while one which produces a pronounced or typical flame generally is near the limit of the capacity of the switch. The life of contact pieces depends to a considerable extent upon the load which the contacts handle, and generally the life is a continuous function of load. Contact life depends largely on erosion. The erosion from a spark generally is only oxidation. The oxide, if not volatile, is removed by the abrasive or cleaning action of the mechanical engagement of the two contact pieces of the gap. A flame actually volatilizes some of the metal of the contact piece. Some of this metal enters the arc stream and thereby is transferred from one contact piece to the other. It is believed that this metal in the arc stream aids the flame-like arc in sustaining itself.

So long as the arc assumes a spark like character a set of contacts may appear to have an indefinitely long life running into millions of cycles of operation. But the same contacts subjected to a heavier load so that the arc assumes a decided flame like character may last only few hundred cycles of operation. And commercial acceptance tests of certain types of heavy duty contactors have specified as few as five operations on a given overload.

It has been observed that the production of a flame-like arc often marks a pronounced reduction in the life of a set of contacts. Therefore it often happens that under certain conditions the life decreases at a greater rate or by a greater percentage than the load increases. The increase in load may consist of an increase in either the current or voltage of the circuit being interrupted.

Under certain conditions a reduction of voltage will be more effective to reduce the tendency for the formation of a flame than a reduction in current. Or to put it differently, a reduction in voltage may permit the contact gap to control more power (product of current and voltage) without increasing the tendency for the formation of a flame.

The common methods of increasing the interrupting capacity of contacts may be summarized as follows:

1. Increasing the length of gap to which the switch contacts separate.

2. Increasing the speed at which the contacts separate.
3. Enlarging the contacts themselves which has the effect of reducing the current density of the arc and/or increasing the heat capacity of the metal parts. In this connection it is to be borne in mind that generally contacts are operated rather infrequently and the heating effect of the arc lasts only a short time. The heat capacity of the contact pieces therefore may be an important factor.
4. Reducing the voltage impressed across individual gaps by putting a number of gaps in series.
5. Making special provisions for preventing or opposing the formation of an arc and for extinguishing it if it does form, such as operating the switch in vacuum or oil, using magnetic blow outs and de-ionizing the gas in the arc.
- 20 The present invention is concerned with the perfection of the fourth of the above methods of increasing the arc interrupting capacity of electric switch contacts. It provides a mechanical system for operating a number of series connected contact gaps so that the load and the voltage properly divides between the several gaps.
- In switches of the series connected gap type it is essential that all gaps should open at the same time. If one gap should open ahead of the others it may interrupt the circuit by itself and sustain the whole load. When this gap extinguishes its arc the circuit is broken and the other gaps opening subsequently have no work to perform.
- 35 If the one contact gap which opens first is unable by itself to interrupt the circuit, it is subjected to a severe flaming arc until one or more other gaps open to help it interrupt the circuit. While the contacts of the gap which opens first suffer the worst, the other contacts also suffer because when those other contacts do open the arc in the first gap, by heating the contact pieces and ionizing the air, will have lowered the resistance of that first gap to make it less effective as a circuit interrupt. It frequently is convenient to provide two contact gaps in a switch by the simple mechanical expedient of providing a movable piece of metal which is bridged across two stationary contact pieces.
- 50 When the movable piece is lifted two contact gaps are established, one between the movable piece and each of the two separate stationary contact pieces. In a switch of this type it heretofore has been the common practice to provide a more or less fixed mechanical arm to operate the movable contact piece. In order to allow for non-uniformity of wear between the separate contact surfaces a resilient connection would be provided between the arm and movable contact piece. This resilient connection would insure that the movable contact would engage both of the stationary contact pieces so as to close the circuit. However, when the contacts would open, one of the gaps generally would open ahead of the other and in so doing it would sustain the brunt of the work of opening the circuit. The arc, which occurred incident to the breaking of the circuit would burn the contact material and in the case of metals, would oxidize it. Where the metal was oxidized, the oxide generally would be worn off rapidly by subsequent operations of the switch. It was inevitable, that the contact surfaces which took the brunt of the arcing in interrupting the circuit should wear more rapidly than the others. Because of this
- greater wear, this faulty condition of early operation of one gap would grow worse as the switch was used until eventually one gap would be doing all the work. The bad effects of uneven distribution of the load in switches heretofore known have not been confined to transferring the total wear to one set of contact pieces. It also has increased the total wear and reduced the capacity of the switch to that of the single contact gap which did all the work of breaking the circuit. Thus, for example, a switch having two contact gaps in series, for a certain type of service might be given a rating of 20 amperes 220 volts. When the switch operated correctly, each gap would control 20 amperes at 110 volts. If the switch should impose the whole load on one contact gap the rating might have to be reduced, for example, to 5 amperes, 220 volts. In other words, the higher voltage per gap reduces the capacity of each gap and the reduced capacity of one gap becomes the total capacity of the whole switch.
- It is a primary object of the present invention to provide an operating mechanism for a switch having a plurality of gaps in series which will insure that all gaps open simultaneously.
- It is a further object of my present invention to provide a supporting and operating mechanism for a bridging contact piece which will automatically align it with the stationary contact pieces with which it is to cooperate.
- It is a further object of my invention to provide means in the operating mechanism of a switch having a number of contact gaps for automatically adjusting, compensating and correcting for uneven wear of contact surfaces and misadjustment resulting from accident or mechanical wear.
- It is a further object of the present invention to provide a mechanism for operating several contact gaps of a switch which will insure that the contacts open simultaneously regardless of large manufacturing tolerances, uneven wear of contact pieces and/or misadjustment of the contacts.
- In order better to acquaint those skilled in the art with the teachings and practice of the present invention, I now shall describe certain specific embodiments thereof, references being made to the accompanying drawings in which:
- Figs. 1 and 2 are a plan and elevation respectively of a relay embodying my present invention.
- Fig. 3 is a partial section taken along the line 3—3 of Fig. 1.
- Fig. 4 is a partial section similar to Fig. 3 but showing the mechanism in a different operated position.
- Fig. 5 is a section taken along the line 5—5 of Fig. 2.
- Figs. 6 and 7 are diagrams for illustrating the operation of the apparatus of my present invention.
- Figs. 8 and 9 are a plan and elevation respectively of another relay having a switch construction embodying my present invention.
- Fig. 10 is an enlarged detail section of a part of the contact mechanism of the relay of Figs. 8 and 9, Fig. 10, being taken along the line 10—10 of Fig. 8 and looking in the direction of the arrows.
- Fig. 11 is a section taken along the line 11—11 of Fig. 10 and looking in the direction of the arrows.
- Figs. 12 and 13 are plan and elevational views

of still another relay having a switch construction embodying my present invention.

Fig. 14 is an enlarged detail section of a part of the switch mechanism of the relay of Figs. 12 and 13, taken along the line 14—14 of Fig. 12.

Figs. 15 and 16 are a sectional elevation and a plan respectively of still another switch construction embodying my present invention.

The relay of Figs. 1 and 2 consists essentially of

10 a set of switch contacts and a magnet for operating the same. The magnet is indicated generally by the reference numeral 10 and comprises a magnet coil 11 and an armature 12. The armature 12 is carried on an iron frame 13 and is secured thereto by means of blind rivets 14 in the armature 12 which engage holes in the frame 13, and also by means of stops 15.

15 The switch contacts comprise a pair of stationary contact pieces 21 and 22 and a bridging contact piece 23. The bridging contact piece 23 is secured by means of an insulator 24 which in turn is riveted to an eye in one end of the bar 25, a clearance hole being provided in the contact 23 for the rivet which secures the insulator 24 to the bar 25. As is best shown in the sectional view of Fig. 3, the bar 25 extends through a slot 27 in a bracket 28 which is carried by the armature 12. The other end of the bar 25 is bent at a right angle at 29 and fits loosely into a hole 30 extending through the bracket 28 and the armature piece 12. A flat strip spring 32 fits closely over the end 29 of the bar 25 so as to prevent it from slipping out of the hole 30; and the end of the spring 32 bears against the rod 25 so that the spring 32 and the bracket 28 firmly grip the rod 25. Except for the grip and force of the spring 32, the bar 25 is free to move in the slot 27 of the bracket 28 and to hinge in the hole 30. Furthermore, the looseness of the fit of the bent end of the bar 25 in the hole 30 permits the bar 25 to rotate, that is, to twist in the grip of the spring 32. The grip of the spring 32 resists this rotation by the friction of the grip. The spring 32 exhibits substantially no resilience in the direction of rotation of the rod 25 and therefore it exerts no force tending to rotate the rod 25 or to restore it to any rotated position. This characteristic of operation results from the fact that the force or restraint of friction is non conservative in that it dissipates and does not conserve to the mechanical system the energy expended in working against it. A resilient restraint, on the other hand, is conservative in that it conserves the energy and returns it later in the form of a restorative effort. The grip of the spring 32 resists but does not produce rotation of the bar 25. Therefore it tends to hold the bar 25 in any position in which it happens to stop.

20 The armature 12 is adapted to be attracted by the magnet 11 so as to move the bridging contact 23 into engagement with the two stationary contact pieces 21 and 22. When the magnet 11 is de-energized, a spring 34 restores the relay substantially to the condition shown in Fig. 2.

25 When the armature 12 is attracted by the magnet 11 it rotates about the bearing provided by the blind rivets 14 thereof which engage the iron frame 13 as shown in Fig. 2. In so doing, it first brings the bridging contact 23 into simultaneous engagement with the two stationary contact pieces 21 and 22. In so doing it may cause the contact piece 23 to operate in approximately the manner illustrated diagrammatically in Fig. 6. Inasmuch as the bar 25 is capable of rotating

30 in the bracket 28, the bridging contact 23 may assume any random position such as the position in which it is shown in solid lines in Fig. 6. As the bar 25 moves it towards the contact pieces 21 and 22, it reaches the position 23A shown in dotted lines in which it engages only the contact piece 21. In this condition it cannot close the circuit controlled by the switch because it does not complete an electrical path between the two stationary contact pieces 21 and 22. Continued motion of the bar 25 causes the bridging contact 23 to rotate into the position 23B also shown in dotted lines in which it engages both the contact pieces 21 and 22 so as to complete the electrical connection between those stationary contact pieces. During the motion just described, the bar 25 has twisted or rotated in the grip of the spring 32 and the bracket 28, but it has not moved in the slot 27. Further motion of the armature 12 towards the magnet coil 11 causes the bar 25 to move in the slot 27 because the bracket 28 is carried by the armature 12 into the position shown in Fig. 4, whereas the bar 25 is prevented from moving therewith due to the engagement of the bridging contact 23 with the stationary contact pieces 21 and 22. This flexes the spring 32, and the force of the spring is borne by the contact pieces 21 and 22. The force of the spring 32 therefore provides the contact pressure.

35 When the bracket 28 continues to move with the armature 12 after the bridging contact 23 has come into engagement with both of the contact pieces 21 and 22 so that the bar 25 moves in the slot 27, the contact piece 23 is forced to slide slightly across the contact surfaces of the contact pieces 21 and 22 so as to provide a slight scouring action. This occurs as follows:

40 The armature 12, when it operates, rotates about its point of fastening indicated approximately by the reference numeral 36 in Fig. 3 where the blind rivets 14 engage the iron frame 13. It is also to be observed that the rod 25 articulates with respect to the armature 12 at its end 29 where it engages the hole 30. After 45 the bridging contact 23 has engaged the two stationary contact pieces 21 and 22, the armature 12 continues to rotate in a counter clockwise direction as viewed in Fig. 3 so that the point 29 continues to describe an arc about the point 36. 50 In so doing, the point 29 moves towards the left as viewed in Figs. 3 and 4, and therefore forces the bar 25 and the contact piece 23 also to move towards the left as viewed in Figs. 3 and 4, and in so doing to wipe the contacting surface of the 55 bridging contact 23 against the contacting surfaces of the stationary contact pieces 21 and 22.

60 The contact piece 23, as it rotates from the position shown in solid lines to the position 23B in Fig. 6, turns in the grip of the spring 32. Inasmuch as the spring 32 exerts only a frictional restraint upon the rotation of the rod 25 in its grip, it shows no tendency whatsoever to rotate the rod 25 so as to bring the contact piece 23 back towards the position 23A. Consequently, 65 when the magnet 11 releases the armature 12, the rod 25 will draw the bridging contact piece 23 away from the stationary contact pieces 21 and 22 without producing any rotation whatsoever of the bridging contact 23. This is illustrated diagrammatically in Fig. 7 where the contact piece 23 is indicated as being moved from the position shown therein in solid lines to the position 23C shown in dotted lines without any rotation thereof whatsoever. If the bar 25 70

- should rotate slightly while the contacts are in engagement and the bridging contact 23 is wiping and rocking over an irregular contour of the contact pieces 21 and 22, this will be immaterial because it will take place before the contact piece 23 disengages the stationary contact pieces 21 and 22. As long as the spring 32 continues to exert contact pressure the bridging contact 23 will engage both of the contact pieces 21 and 22.
- 10 When the bracket 28 again comes into engagement with the rod 25 and thereby removes the pressure from the contact surfaces of the several contact pieces 21, 22 and 23, the contact piece 23 begins to move away from the two stationary contact pieces. As it does so, it is held in the grip of the spring 32 and the bracket 28 and it is frictionally restrained from rotating. Consequently, it disengages the two stationary contact pieces 21 and 22 simultaneously.
- 20 Because the spring 32 can exert no force tending to rotate the rod 25, it must of necessity withdraw the bridging contact 23 from the stationary contact pieces 21 and 22 without rotation. Therefore, it cannot open one contact gap ahead of the other. Since the spring 32 exerts some frictional restraint at all times upon the bar 25 to prevent rotation thereof, the bridging contact 23 will not rotate under its own weight should it be slightly out of balance.
- 30 It is thus seen that the alignment of the contacts is effected incidentally to the closing operation of the switch so as to insure that both gaps will open simultaneously when the switch is required to interrupt the circuit. This characteristic of operation of the switch is obtained by supporting the mechanism of the switch so as to permit it to rotate and so as to impose a frictional restraint, and also eliminate any resilient restraint upon rotation. It is only a resilient restraining force which can act as a restoring force to produce a rotation of the bridging contact piece 23 during the opening operation of the switch.
- 40 Figs. 8 and 9 illustrate a relay embodying my invention in which mechanism is provided for insuring that four contact gaps open simultaneously. Therein, an armature 41 carries a bracket 42 which in turn carries a spring 43 and a bar 44 which latter has a turned end 45 which catches loosely in a hole 46 in the bracket 42 and armature 41, all of which is similar to the construction illustrated in Figs. 1 to 4 inclusive. The round bar 44 has welded thereto at its outer end, a cross bar 48 which lies substantially at a right angle to the bar 44. The opposite ends of the rod 48 carry round insulators 49 and 50 which in turn carry bridging contacts 51 and 52. The bridging contact 51 is adapted to engage stationary contact pieces 55 and 56, and the bridging contact piece 52 is adapted to engage stationary contact pieces 57 and 58. The construction of the bridging contact 52 is more clearly illustrated in the enlarged sectional detail views of Figs. 10 and 11. As shown in Figs. 10 and 11, the bridging contact 52 comprises a pair of formed conducting pieces 61 and 62 which fit loosely into a circumferential groove in the insulator 50 and which are riveted together so as to be held thereby on the insulator 50. The insulator 50 fits tightly onto the rod 48 so as to be nonrotatable thereon. The conducting pieces 61 and 62 which constitute a part of the bridging contact 52 fit loosely onto the insulator 50 so as to permit the bridging contact 52 to rotate thereon. A spring or resilient member 64 gripped between the pieces 61

and 62 bears against the insulator 50 so that the insulator 50 is gripped between the spring 64 and the conducting piece 61. This grip frictionally restrains rotation of the bridging contact 52 about the insulator 50.

5 A pin 54 in the insulator 50 is adapted to engage the edges of a notch in the arcuate center portion of the piece 61 so as to limit the rotation of the bridging contact 52 about its insulator 50. A similar pin 53 limits the rotation of the bridging contact 51 about its insulator 49. These pins 53 and 54 may be omitted if desired because in general no harm can result from the bridging contact accidentally being brought into engagement with only one of its stationary contact 15 pieces (assuming that the switch is open). However, it is important that the bar 44 be limited in its rotation in order that one of the bridging contacts may not be brought accidentally into engagement with both its stationary contact 20 pieces. A two pole switch usually is so wired as to interrupt both sides of a two wire line and thereby to isolate the load completely from the source of power. If the switch of Figs. 8 and 9 were so used and if one of the bridging contact 25 pieces were permitted accidentally to touch both its stationary contact pieces at one time the load thereby would be connected to one side of the line. Such a situation could constitute a hazard.

30 Rotation of the bar 44 is limited by the bent end 45 of the rod 44 engaging sides of the hole 46 in the bracket 42 and armature 41 in which the bent over end 45 of the rod 44 is inserted.

35 The relay of Figs. 8 and 9 is adapted to be connected to control both wires of a two wire line so that when the switch is open both sides of the line are completely disconnected from the load. Thus one side of the line may be connected to each of the stationary contact pieces 55 and 57 and the load may be connected to the 40 stationary contact pieces 56 and 58. With such an arrangement, the four contact gaps of the relay are in series.

45 It is to be observed that the switch mechanism of the relay of Figs. 8 and 9 provides four contact 45 gaps to be operated by the armature 41 and that it employs three frictionally restrained automatic adjustments.

50 The three frictionally restrained adjustments of the mechanism permits the force exerted by the spring 43 to be substantially equally distributed among the four contact gaps, and compels those four contact gaps to open simultaneously. Thus, the friction grip of the bridging contact 52 on the insulator 50 causes the bridging contact 52 to disengage the stationary contacts 57 and 58 simultaneously and, similarly, the frictional engagement of the bridging contact piece 51 with the insulator 49 causes the bridging contact 51 to disengage the stationary contact pieces 55 and 56 simultaneously. The frictionally restrained rotation of the bar 44 under the spring 43 causes the two bridging contacts 51 and 52 to leave their respective pairs of stationary contacts simultaneously.

55 It may be stated as the general rule that each contact gap of the switch in excess of one contact gap requires a separate adjustment or degree of freedom in order that the operating mechanism automatically may align the contacting pieces so as to open all contact gaps simultaneously.

60 The switch of Figs. 1 and 2 has two contact gaps and therefore employs a mechanism providing one adjustment, or one degree of freedom 70

in adjustment. This single adjustment or single degree of freedom is provided by the rod 25 which is rotatable in its support. The switch of Figs. 8 and 9 which has four contact gaps employs mechanical connections providing three separate adjustments, or adjustments providing three degrees of freedom. These three adjustments or degrees of freedom are provided by the three separate mechanisms or mechanical connections already described and enumerated.

Figs. 12 and 13 illustrate a switch mechanism having one mechanical connection which in itself provides two degrees of freedom of adjustment. In Figs. 12 and 13 an armature 71 of the relay carries an arm 72 which is secured resiliently to the armature 71. As is shown more clearly in the sectional detail of Fig. 14, the arm 72 is perforated at its outer end to receive a pin 73. Pin 73 carries a contact disk 75 which is formed at its center to fit a spherical head 76 of the pin 73. The pin 73 extends through a large clearance hole in the contact disk 75 and also through a collar 77 which has a curved surface which also fits the curvature of the formed center portion of the contact disk 75. A coil spring 78, which bears against a washer 80 secured to the pin 73 by a cotter pin 79 or the like, causes the spherical head 76 and the collar 77 to firmly grip the formed center portion of the contact plate 75. The plate 75 is permitted to slide in the grip of the head 76 and collar 77. This gives the contact plate 75 two degrees of freedom of adjustment and permits it to align itself with three stationary contact pieces. The plate or disc 75 has two degrees of freedom of adjustment because it is free to rotate independently about two different axes of rotation for adjusting the relative order of opening of the contact gaps.

As is illustrated in Figures 12 and 13, the contact plate 75 is adapted to engage three stationary contact pieces 81, 82 and 83 when the armature 71 is in its normal or released position, and to engage three other stationary contact pieces 84, 85 and 86 when the armature 71 is in its drawn up position. It is immaterial that the contact plate 75 may have to adjust itself to a slightly different position for engaging each of these two sets of three stationary contacts. It will automatically align itself with each set of contacts as it engages the same and then will act to disengage all three of those stationary contact pieces simultaneously.

If it is desired, the clearance hole in the formed central portion of the disc 75 may be made small to limit the motion and range of adjustment of the plate 75. However, since the contact disc 75 of the relay of Figures 8 and 9 engages stationary contacts in both the normal and released positions of the relay, the disc 75 is not subject to accidental misalignment, and it should not be necessary to limit its range of adjustment. If either one of the two sets of stationary contacts should be omitted, then it might be desirable to limit the range of adjustment of the disc 75.

The contact disc 75 preferably is made round as shown so that it may rotate about the axis of the pin 73 without affecting its operation or its ability to engage the several stationary contact pieces. The switch of Figures 12 and 13 may be employed for opening a three phase star connected circuit. Thus each of the three branches of the load may be connected between a separate conductor of the three phase line and a separate one of the three stationary contacts of the group 84, 85, 86. While the three contact gaps of such

an arrangement will not be in a single series circuit, each gap will be separately in series with the other two. Therefore, if one gap fails to open it imposes an additional load on each of the others. The switch of Figs. 12 and 13 also may be employed for controlling two load circuits which are to be disconnected from each other when de-energized. Thus one side of a two wire line may be connected to the stationary contact piece 84 and one side of each load may be connected to a separate one of the two stationary contact pieces 85 and 86. The other sides of the loads may be connected to the other side of the line. The gap at the contact piece 84 then will be in series separately with each of the gaps at the contact pieces 85 and 86.

In Figs. 15 and 16 I have illustrated a contact mechanism providing five degrees of freedom for operating simultaneously six contact gaps. Therein, an operating arm 91 is provided with a spherically formed portion 92 which is gripped by concave and convex collars 93 and 94 under the pressure of a spring 95, all of which is carried on a rod 96 which passes through a clearance hole in the center of the formed portion 92. This construction is similar to the mounting of the contact disc 75 of Figs. 12, 13 and 14 and provides two degrees of freedom of adjustment. The arm 91 may be resiliently secured to an armature of a relay magnet in the same manner as is the arm 72 of Figs. 8 and 9. The rod 96 is bent at 97 and at its end 98 carries an insulator 99 which in turn carries a bridging contact piece 100 which is adapted to rotate on the insulator 98 but is frictionally restrained from doing so. The bridging contact 100 and its insulator 99 are of a construction similar to that of the bridging contact 52 and its insulator 50 illustrated in Figs. 10 and 11. Welded to the rod 96 is another rod 102 carrying insulators 103 and 104 at opposite ends thereof. The insulators 103 and 104 in turn carry bridging contacts 105 and 106 which are similar to the bridging contact 100. These three bridging contacts 100, 105 and 106 are adapted to engage six stationary contacts shown in Fig. 16 and numbered 107 to 112 inclusive. This provides six contact gaps which, because of the five degrees of freedom of adjustment provided in the operating mechanism, are controlled to open their gaps simultaneously.

A pair of stops or guides 99 and 100 depend from the arm 91 on opposite sides of the end 98 of the rod 96. This prevents rotation of the whole contact assembly about that portion of the rod 96 which carries the collars 93 and 94 and thereby keeps the several bridging contacts 100, 105 and 106 in positions to engage their respective stationary contact pieces. As in the case of the switch of Figs. 8 and 9, the clearance hole in the formed portion 92 of the arm 91 may be made small to limit the range of the adjustment provided thereby.

While I have shown and described certain specific embodiments of my present invention, it will be apparent to those skilled in the art that the same are by way of illustration only. Therefore, I do not wish to be limited except by the scope of the appended claims.

I claim:

1. In combination, contact pieces adapted to provide a plurality of contact gaps, a single actuator for the contact pieces of all said contact gaps, said actuator being adapted to hold all said gaps open simultaneously and being adapted also to hold all said gaps closed simultaneously, said

- actuator including adjustable mechanical connections interconnecting the contact pieces of all said gaps to provide a contact pressure equalizing system such that a change of contact pressure in any one gap can produce a change of pressure in all other contact gaps, and means for restraining said mechanical connections to oppose the equalization of contact pressures, the restraining forces being substantially non-restorative.
2. In combination, contact pieces adapted to provide a plurality of contact gaps, a single actuator for the contact pieces of all said contact gaps, said actuator being adapted to hold all said gaps closed simultaneously, said actuator including mechanical connections interconnecting said contact pieces, said connections being adjustable as respects the relative order of closing said contact gaps to the extent of a number of degrees of freedom which number is one less than the number of said contact gaps, and means for imposing restraints on all said adjustments, said restraints involving only forces which are substantially non-restorative.
3. In combination, contact pieces adapted to provide a plurality of contact gaps, a single actuator for the contact pieces of all said contact gaps for closing all said gaps, said actuator including mechanical connections interconnecting said contact pieces, said connections being adjustable as respects the relative order of closing said contact gaps to the extent of a number of degrees of freedom which number is one less than the number of said contact gaps, and means for imposing non-restorative restraints on all said adjustments.
4. In combination, a pair of contact pieces, a bridge contact adapted to lie in simultaneous engagement with both said contact pieces, first means for moving said bridge contact into and out of engagement with said contact pieces, mounting means for mounting said bridge contact on said first means so as to cause said bridge contact to be carried by said first means but permitting said bridge contact to orient itself with respect to said contact pieces to alter the order in which it engages said separate contact pieces, said mounting means including means for imposing a restraint upon the orientation of said bridge contact piece, said restraint consisting solely of forces which are non-restorative.
5. In combination, a pair of contact pieces, a bridge contact adapted to lie in simultaneous engagement with both said contact pieces, first means for moving said bridge contact into and out of engagement with said contact pieces, mounting means for mounting said bridge contact on said first means so as to cause said bridge contact to be carried by said first means but permitting said bridge contact to orient itself with respect to said contact pieces to alter the order in which said bridge contact engages said separate contact pieces, said mounting means including means for imposing a restraint upon the orientation of said bridge contact, said restraint consisting solely of forces which are non-restorative, said mounting means including also a member carrying said bridge contact which is rotatable with respect to said first means.
6. In combination, a pair of contact pieces, a bridge contact adapted to lie simultaneously in engagement with both contact pieces of said pair, first means for moving said bridge contact into and out of engagement with said contact pieces, mounting means for mounting said bridge contact on said first means so as to cause said

bridge contact to be carried by said first means but permitting said bridge contact to orient itself with respect to said contact pieces to alter the order in which said bridge contact engages said separate contact pieces, said mounting means including means for imposing a frictional and substantially non-resilient restraint upon the orientation of said bridging contact piece.

7. In combination, a bridge contact, means for mounting said bridge contact so as to permit it to rotate about an axis, a pair of separate contact pieces adapted to engage and bear against said bridge contact, so that the separate pressures of said separate contact pieces tend to rotate said bridge contact in opposite directions about said axis, and means imposing a non-restorative restraint upon the rotation of said bridge contact about said axis.

8. In combination, contact pieces adapted to provide two contact gaps, a single actuator for the contact pieces of both said gaps, said actuator being adapted to hold both of said gaps open simultaneously, adjustable mechanical connections between the actuator and the separate contact pieces for permitting one of said gaps to be lengthened by shortening the other while said actuator is stationary, said connections including means for imposing a frictional restraint upon the lengthening and shortening of said contact gaps as aforesaid, said actuator and said connections also including means for imposing a force of such magnitude on each contact piece as to provide a contact pressure at each of said gaps in excess of the pressure that would be required at that gap for overcoming said frictional restraint in the absence of any pressure at the other gap.

9. In combination, contact pieces adapted to provide two contact gaps, a single actuator for said contact pieces, said actuator being adapted to hold both of said contact gaps open simultaneously, adjustable mechanical connections between said actuator and the contact pieces of said gaps, said connections being adjustable to alter the order in which said contact gaps close, said connections including means for imposing a non-restorative restraint upon the adjustment of the order of operation of said gaps, said non-restorative restraint being adapted to provide forces of such magnitude as to produce separately at each gap a component of contact pressure in excess of any component of pressure produced at said gap by any restorative force which acts to restrain the alteration of said order of operation of said contact gaps.

10. In combination, a switch base, an actuator movable with respect to said base and having a slot on a movable portion thereof, the long dimension of said slot lying in a direction which is less than 90 degrees from the direction of motion of said movable portion, a round rod having a first portion thereof engaging said slot, said rod being rotatable in said slot, said rod also being movable in said slot laterally with respect to itself and longitudinally with respect to said slot, said actuator including means for limiting the motion of said rod towards one end of said slot, a spring engaging said rod and urging it towards said one end of said slot, said spring being ineffective to rotate said rod about the axis of said rod, a bridging contact carried by said rod at a second portion thereof, said bridging contact having contacting portions located on opposite sides of a first plane containing the axis of said rod, two stationary contact pieces on said base each

of which has a contacting portion adapted to be engaged by a separate one of said contacting portions of said bridging contact, said stationary contact pieces having their contacting portions 5 on opposite sides of a second plane containing the axis of said rod and making an angle of less than 90 degrees with that component of the direction of motion of said movable portion of said actuator which is perpendicular to the axis 10 of said rod, said stationary contacts also having their contacting portions on the same side of a third plane containing the axis of said rod and making an angle of 90 degrees with the second plane.

11. In combination, contact mechanism providing a plurality of contact gaps, said mechanism including stationary contact pieces and a movable member which is required to be aligned with said stationary contact pieces, an actuator 20 member movable with respect to said stationary contact pieces, a mechanical connection between said actuator member and said movable member for mounting said movable member on said actuator member to be carried thereby, said connection comprising means on one of said members 25 for resiliently gripping the other, said other member being movable in the grip thereof to orient the movable member with respect to said stationary contact pieces, said means being substantially ineffective resiliently to restrain the movement of said other member in said grip, whereby 30 said other member is frictionally and substantially non-restoratively restrained from moving with respect to said one of said members, and electric circuit connections connecting said contact gaps in series with each other in an electric circuit.

12. In combination, contact mechanism providing a plurality of contact gaps, said mechanism including stationary contact pieces and a movable member which is required to be aligned with said stationary contact pieces, an actuator 40 member movable with respect to said stationary contact pieces, a mechanical connection between

said actuator member and said movable member for mounting said movable member on said actuator member to be carried thereby, said connection comprising spherically concave and convex gripping pieces and a spring on one of said members, the other member having a spherically curved portion gripped by said gripping pieces, said other member being movable in the grip of said gripping pieces, said gripping pieces and spring being substantially ineffective resiliently 10 to restrain movement of said other member in said grip, whereby said other member is capable of rotating with respect to said first member independently about two different axes but is frictionally and substantially non-restoratively restrained from so rotating, and electric circuit connections connecting said contact gaps in series with each other in an electric circuit.

13. In combination, contact mechanism providing a plurality of contact gaps, said mechanism including stationary contact pieces and a movable member which is required to be aligned with said stationary contact pieces, an actuator member movable with respect to said stationary contact pieces, a mechanical connection between said actuator member and said movable member for mounting said movable member on said actuator member to be carried thereby, said connection comprising means on one of said members 20 for resiliently gripping the other, said other member having a cylindrical portion gripped by said means, said cylindrical portion being rotatable in the grip of said means to orient the movable member with respect to said stationary contact pieces, said means being substantially ineffective resiliently to restrain rotation of said other member in said grip, whereby said other member is frictionally and substantially non-restoratively restrained from rotating with respect to said one of said members, and electric 25 circuit connections connecting said contact gaps in series with each other in an electric circuit.

KARL H. SOMMERMEYER.
